UNITED STATES PATENT OFFICE.

EUGENE A. SISSON, OF WORCESTER, MASSACHUSETTS, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

POCKETED CARRIER.

1,310,377.

Specification of Letters Patent. Patented July 15, 1919.

Application filed September 25, 1918. Serial No. 255,547.

To all whom it may concern:

Be it known that I, EUGENE A. SISSON, a citizen of the United States, residing at Worcester, in the county of Worcester, State 5 of Massachusetts, have invented a certain new and useful Improvement in Pocketed Carriers, of which the following is a specification, reference being had therein to the accompanying drawings.

10 The invention has relation to pocketed carriers of the class comprising those which are used for holding and carrying cartridges.

15 The general object of the invention is to solve the problem of satisfactorily combining with a pocketed carrier having one or more pockets of normal size, one or more covered pockets of the character required for accommodating the magazines of automatic pistols. The separately-formed 20 pocket-pieces provided with covered pockets for such purpose which heretofore have been applied to carriers such as aforesaid have constituted cumbrous, bulky, inconvenient, 25 and unsatisfactory additions.

30 The invention consists essentially in a carrier having woven upon the band or body-portion thereof, alongside one or more pockets of a normal size, one or more supplemental narrow vertically elongated pockets adapted to contain a pistol magazine and provided with a cover or covers 35 permanently attached to said band or body portion.

40 Pocketed carrier-webs embodying the invention are more conveniently, expeditiously, and otherwise advantageously produced if the pistol magazine pockets do not exceed in total depth the width of the band or body-portion on which they are formed.

45 In such case the pistol-magazine pockets are proportioned so as to contain only the lower portion, say two-thirds, of the length of a pistol-magazine. When the pistol-magazine

50 pockets are thus proportioned, which in some respects is advisable, the cover-flaps respectively are provided with a long shank-portion equaling in length vertically the exposed upper portion, approximately one-third of the length of a pistol-magazine.

When in its closed and fastened condition a cover-flap made to provide such long shank-portion extends upward above the body or band-portion of the carrier in the

form of an upstanding loop. To afford 55 complete protection to the portion of the pistol-magazine which stands up above the top of its pocket within this loop, the cover-flap preferably is made of hood or box-shape so as by its side flanges to inclose such 60 portion of the pistol-magazine.

An embodiment of the invention is illustrated in the drawings, in which latter,—

Figure 1 is an isometric of a portion of a carrier containing the said embodiment. 65

Fig. 2 is a view of the supplemental pocket in side elevation, with the band or body-portion of the carrier in vertical section alongside the said pocket, and with the cover-flap closed down over the pocket and 70 fastened.

Having reference to the drawings,—

The carrier that is partly shown therein is of the well-known class in which the pockets are woven upon the band or body-portion 1, so that they are integral therewith. Two narrow, vertically elongated, supplemental pockets, 2, 2, are formed upon said band or body-portion in this instance, in addition to the pockets 3, 3, of normal 80 size. The latter pockets are shown as of ordinary proportions suitable to hold cartridges in clips, although it is not essential to the invention that the pockets 3, 3, should be utilized for holding cartridges. The 85 pockets 3, 3, are shown provided with cover-flaps 4, 4, which as usual are made fast by their inner ends to the top of the body or band-portion 1 and are adapted to fold over the pocket-tops. Such cover-flaps are shown 90 as having applied thereto the socket-members 5, 5, of fastener-devices of the glove-fastener type, for engagement with stud-members 6 carried by the pocket-fronts.

The supplemental pockets 2, 2, of this 95 embodiment of the invention do not exceed in depth the width of the band or body-portion 1. Consequently the procedure in weaving the same upon the band or body-portion is equally simple with that in weaving ordinary pockets, and is without the complications incident to the production of pockets of depth exceeding the said width. 100

105 Preferably, though not necessarily in the case of all embodiments of the invention, a single cover-flap 7 is provided for the two narrow pockets 2, 2. The inner end of such cover-flap is attached permanently to the

carrier, in this instance by having the attaching end of the shank-portion 7^a of the cover-flap inserted into the same housing-slit in the top of the carrier that receives the attaching ends of the cover-flaps 4, 4, of the other pockets, and secured therein by the line 8 of fastenings, usually stitches. Fastener-members like those of the other pockets are shown combined with the pockets 2, 2, and their cover-flap. On account of the width of the said cover-flap it is furnished with two socket-members 5^a, 5^b, applied at opposite sides of mid-width thereof for coöperation with stud-members 6^a, 6^b, applied to the fronts of the respective pockets 2, 2.

As mentioned hereinbefore, the pockets 2, 2, are proportioned so that they contain only the lower portion, in this case about two-thirds, of the length of the pistol-magazines 9, 9, which are placed within such pockets, leaving about one-third of the length of the respective magazines exposed above the tops of the pockets 2, 2, when the latter are uncovered. The shank-portion 7^a of the cover-flap 7 is correspondingly elongated to equal in length this upstanding portion of the length of the magazines, as indicated best in Fig. 1, so that when the said cover-flap is closed down over the pockets and their contained magazines the cover-flap forms an upstanding loop over said portion of the magazines. The preferred hood or box-shape of the cover-flap 7 is shown in the drawings, its side-flanges 7^b, 7^b, being shown best in Fig. 1, and the

manner in which they close in and protect the upstanding portion of the pistol-magazine being represented in Fig. 2.

What is claimed as the invention is:—

1. A woven pocketed carrier having woven upon the band or body-portion thereof of one or more wide pockets of normal size, and one or more narrow vertically elongated pockets corresponding vertically with the width of the said portion, adapted to contain the lower portion of a pistol magazine, and provided with a cover-flap for the said pocket or pockets made with a long shank-portion equaling in length the exposed upper portion of the length of the said magazine.

2. A woven pocketed carrier having woven upon the band or body-portion thereof of one or more wide pockets of normal size, and one or more narrow vertically elongated pockets corresponding vertically with the width of the said portion, adapted to contain the lower portion of a pistol magazine, and provided with a cover-flap for the said pocket or pockets made with a long shank-portion equaling in length the exposed upper portion of the length of the said magazine, and also made of hood or box shape to protect laterally by its side flanges the upstanding portion of a magazine.

In testimony whereof I affix my signature in presence of two witnesses.

EUGENE A. SISSON.
